UNITED STATES PATENT OFFICE

BYERS W. KADEL, OF BALTIMORE, MARYLAND, ASSIGNEE, BY MESNE ASSIGNMENTS,
TO THE SYMINGTON COMPANY, A CORPORATION OF MARYLAND

JOURNAL BOX

Application filed January 23, 1924. Serial No. 688,034.

The invention relates to journal boxes for railway cars and, generally considered, involves the production of a journal box of reliable construction which can be economically manufactured.

One of the principal objects of the invention is to provide a journal box composed of a plurality of sections, one of which is formed of wrought metal and another of which is formed of cast or forged metal, said sections being advantageously united to provide a composite journal box of exceedingly strong construction but comparatively light weight.

Another object of the invention resides in the provision of a composite journal box in which the lower portion may be readily formed of pressed metal and the upper portion thereof cast or forged, said upper and lower portions being preferably united by welding along, or at intervals along, the lines of juncture of said portions.

A further object of the invention is to produce a journal box having a cast roof portion and a pressed metal oil well portion, said portions being rigidly united to form a very strong but comparatively light weight journal box while maintaining the several dimensions thereof according to the A. R. A. standards.

A still further object of the invention is to provide a composite journal box of the class described in which the inner dust guard wall is formed of a pressed metal plate retained within recesses formed by the shaping of the outer dust guard wall formed integrally with the pressed metal oil well portion of the journal box.

With these and other objects in view the invention further consists in the particular construction and arrangement of the several parts hereinafter described and pointed out in the claims.

In the drawings chosen to illustrate the invention:

Figure 1 is a side elevation of a journal box constructed in accordance with my invention.

Figure 2 is a top plan view thereof, a por-

tion of said box being shown in horizontal section.

Figure 3 is a vertical central longitudinal sectional view.

Figure 4 is a vertical transverse sectional view on the line 4—4 of Figure 3.

Referring to the drawings in which corresponding reference characters designate similar parts in the several views, the journal box involves a cast metal roof portion 1 having connected thereto a wrought metal oil well section 2. The roof or upper portion of the journal box may be of any desired construction for co-action with adjacent portions of the car truck side frame and is also provided with the usual means for supporting the journal box lid (not shown herein). The journal box roof section 1 is provided with depending side walls 3, each of said walls being offset at their lower ends, as indicated at 4. The rear end of the roof section is preferably provided with spaced portions 5 and 6 forming the upper part of the dust guard well lying between the inner and outer dust guard walls.

The oil well portion of the journal box is formed of wrought metal which may be either forged, pressed or otherwise shaped corresponding to the contour of the journal box desired. The upstanding walls 7 of the oil well portion are preferably offset, and formed with brass lug portions, as indicated at 8, said offset portions coacting with the offset portions 4 of the depending walls 3 in providing a very rigid interconnection between the upper and lower sections of the journal boxes.

As shown in the present construction, the offset portions 8 are disposed inwardly of the offset portions 4, although it will be understood that the reverse of this construction may be equally well utilized and I do not wish to be understood as limiting the invention to any particular disposition of the adjacent portions of the roof and oil well sections of the journal box. According to the showing herein, it will be observed that the upper edge portions of the walls 7 are firmly seated in the shouldered portions of the depending walls 3 and that the adjacent offset portions 4 and 8 are disposed in overlapped

relation for effectively resisting lateral or side thrusts.

Weld means is preferably utilized to unite the overlapped portions of the roof and oil well sections of the journal box, said weld means extending throughout the length of the joints or at spaced intervals, by spot welding, as may be desired. While I have referred to weld means as serving to rigidly unite the parts, it will be understood that I do not so limit the invention in that other means may be advantageously used to effect a rigid union between the overlapped portions. As shown, the joints are preferably disposed horizontally of the journal box, said joints, however, being preferably inclined upwardly at the front end of the journal box, at a relatively large angle for example between 30° and 60° from the horizontal, as indicated at 9. It will be observed that the relative depth of the overlapping of the adjacent portions may be varied, as shown, the depth of the overlapped portions intermediate the length of the box being relatively increased.

The pressed metal oil well section of the journal box is preferably offset at its inner end to provide a partially surrounding recess 10, the innermost portion of said oil well section being bent adjacent said recess to form the outer dust guard wall 11. The outer dust guard wall 11 is disposed in alinement with the outer dust guard wall portion 6 of the roof section, as shown. The inner dust guard wall preferably comprises a detachable plate 12, said plate having a flange 13 adapted to fit within the recess 10 and maintain the plate in spaced relation to the outer dust guard wall 11. The plate 12 is disposed in alinement with the inner dust guard wall or guide portion 5 of the roof section, as clearly shown. By this construction it will be observed that a satisfactory dust guard wall is produced, and while the detachable plate 12 need not necessarily be oil-tight, it will be noted that it serves to prevent the waste from working back and in addition functions as a dust guard guide. In the embodiment disclosed, it will be seen that complete removal of the plate 12 after assembly is prevented by the roof portion of the box.

A journal box manufactured in accordance with the present invention provides a very advantageous construction in which all of the measurements of the A. R. A. standards are readily maintained.

It will also be observed that the relative variation in depth of the overlapped portions permits of an advantageous construction whereby selected portions of the sections can be economically and very rigidly united, the intermediate overlapped portions of said sections serving to interlock the roof and oil well sections against relative longitudinal movement. The upward inclination of the

joint at the front end of the journal box also provides for a more rigid interconnection of the sections while maintaining all of the structural advantages of the cast integral journal box as now manufactured. It will also be noted that the line of weld is spaced from the bottom of the brass lug portions of the roof section. 70

I claim:

1. A journal box involving a cast metal roof section having spaced portions forming inner and outer dust guard walls, a wrought metal oil well section connected to said roof section, said oil well section having a portion shaped to provide an outer dust guard wall disposed in alinement with the dust guard wall of the roof section, a detachable inner dust guard wall insertible in said oil well portion, and means retaining said last named dust guard wall in alinement with the inner dust guard wall of said roof section, said roof section fitting over said detachable guard wall and preventing removal thereof. 75 80 85

2. A journal box comprising a cast metal roof section, a wrought metal oil well section, and means rigidly uniting said sections, said means including overlapped portions of the sections, the overlapped portions of the oil well section being inwardly disposed with respect to the corresponding portions of the 90 95 roof section.

3. A journal box involving a cast metal roof section having brass lug portions, a pressed metal oil well section having complementary brass lug portions, and weld means uniting said sections, the corresponding brass lug portions of the sections being offset in 100 105 opposite directions and similarly united.

4. A journal box comprising a top section having spaced portions forming inner and outer dust guard walls, a bottom section connected to said top section, said bottom section having a portion shaped to provide an outer dust guard wall normally in alinement with a dust guard wall of the top section, and a 110 115 separate inner dust guard wall receivable in said bottom section in alinement with the inner dust guard wall of said top section and prevented from removal by said top section fitting thereover.

5. A journal box comprising a top section and a bottom section, said sections having overlapped portions with those on the bottom section inwardly disposed with respect to the corresponding portions of the top section 120 for uniting said sections. 115

6. A journal box comprising top and bottom sections with complementary brass lug portions, the corresponding brass lug portions on the sections being offset in opposite 125 directions, and means uniting said sections.

In testimony whereof I affix my signature.
